UNITED STATES PATENT OFFICE.

GEORGE E. INMAN, OF EAST CLEVELAND, OHIO, ASSIGNOR TO GENERAL ELECTRIC COMPANY, A CORPORATION OF NEW YORK.

METHOD AND APPARATUS FOR TREATING FILAMENTS.

Application filed June 9, 1926. Serial No. 114,808.

My invention relates to methods and apparatus for coating incandescent lamp filaments and other articles of like proportions. More particularly, my invention relates to methods and apparatus for applying the so-called "getter" to coiled metal filaments. Getters are materials, usually non-metallic, which are used in incandescent lamps and similar devices in some cases for improving the vacuum and for preventing discoloration of the bulb. It is desirable that this material be applied uniformly, and this is a more difficult operation in the case of coiled filaments than in that of straight filaments. The present invention is an improvement on that disclosed in my co-pending application, Serial No. 107,883, filed May 10, 1926. The specific method disclosed in that application consists in spraying getter material upon the filaments which are held in a receptacle and simultaneously causing a whirling movement of the filaments in the receptacle. According to the present invention, the filaments are supported in a receptacle connected to the bottom of which is a pipe through which air pressure is directed and means are provided whereby the getter is incorporated with the blast so that the blast accomplishes a double purpose of gettering and stirring up the filaments. One advantage which this has over the specific method disclosed in my application above referred to is that there is less tendency of the tangling of the coils, and this is of particular importance in the gettering of the smaller diameter filaments which are more easily tangled. Further features and advantages of my invention will appear from a description which follows of a species thereof.

In the drawing, Fig. 1 is an elevation partially in section of an apparatus embodying my invention; Fig. 2 is an enlarged fragmentary vertical section through the spray nozzle; Fig. 3 is a top plan view of the spray nozzle; and Fig. 4 shows a portion of a filament coil on an enlarged scale.

The inverted cone or funnel 10 is of brass or other metal which will not be affected by the getter material and contains a number of the filament coils 11. The said funnel is removably supported by an arm 12 which has projecting therefrom a stop pin 13 and is held by the socket bracket 14. A spring 15 surrounds the end of the arm 12 within

the socket, said arm being provided with a pin 16 engaging the end of the spring. The arrangement is such that the arm 12 may be pulled out from the socket but is normally retracted by the spring 15 with the pin 13 resting in the notch in the socket end. The bracket 14 is supported on a standard 17 carried by the base 18. The getter container or graduate 19 is supported on an adjustable bracket 20 carried by the standard 17. This container is adapted to receive a quantity of the getter material comprising finely divided chemicals such as cryolite in suspension in a volatile liquid carrier. One mixture which has been found to be suitable was made by adding two hundred grams of cryolite finely divided to one hundred and fifty grams of lacquer containing amyl acetate and then diluting by adding to one part of the cryolite lacquer mixture four parts by volume of a mixture of 80% methyl alcohol and 20% ether. A nozzle tube 21 extends vertically upward from a point near the bottom of the graduate 19 and the upper end thereof is screwed into a nozzle 22, the latter having a flange 23 which is held in a seat in the bottom of the nozzle adjusting member 24 by a lock nut 25. The internal thread on member 24 engages the external thread on the spray nozzle 26 through the center of which extends the getter material nozzle 22, all of said parts being supported at the bottom of the tubular portion of the funnel 10. An air blast conduit 27 controlled by valve 28 communicates through the wall of the funnel extension 10 with an annular chamber 29 formed between nozzle 26 and said funnel extension 10 which chamber communicates by means of ports 30 with an annular passage 31 formed between the nozzle members 22 and 26. A needle 32 extends up through the center of the nozzle members 21 and 22, and its point is disposed in the constricted end of the member 22. The said needle is bent so that its opposite end is held by one jaw of a control member 33 (Fig. 1) by means of which the operator can move the needle point up and down to control the opening at the end of the getter nozzle, or, if need be, to interrupt the flow of the getter material. An injector tube 34 is provided extending to the bottom of the graduate 19 and with its other end in a suitable position so that air may be injected to stir up the getter mixture. Over the top of 110

the funnel 10 is disposed the filament coating chamber up into which the filaments are blown and simultaneously coated. As specifically shown in the drawing, this chamber 5 is walled by a cylinder 35, preferably of glass, which is supported by the standard 17, a strap 36 surrounding the same being removably and adjustably supported on a bracket 37 which is pivoted on the standard 17. The arrangement is such that the cylinder 35 can be raised from the funnel 10 and swung out of line therewith until a pin 38 carried by the bracket 37 engages a stationary rest 39 supported from the aforesaid standard.

The cylinder 35 is provided at its upper end with a ventilated cover which may be of the same material as that of the funnel 10. The said cover comprises an annular member 40 and a top member 41. The annular member is constructed so that it rests upon the top rim of the cylinder 35 and is held in position by means of a plurality of set screws 42. A secondary support is 25 also provided for the said annular member 40 which consists of a strap 43 having extending therefrom the vertical braces 44 which are attached to the annular member 40 by means of the screws 45. In the upper 30 portion of the annular member 40 is supported the top member 41 by the set screws 46. The top member is adjustably spaced from the annular member 40 so as to allow the escape of gases while at the same time 35 retaining the filaments in the cylinder 35.

In operation, with the cylinder 35 swung over so that the bracket pin 38 rests on the stop 39, a quantity of filament coils are placed in the funnel 10. The cylinder is 40 then swung back to the position shown in the drawing and the air pressure is turned

on causing the getter solution to be aspirated up into the blast. This causes the filament coils to be tossed upwardly into the gettering chamber giving the appearance of a fountain. The gettering mixture is so constituted that it dries very quickly upon striking the coils and the result is that they are rapidly and evenly coated with the getter material. This usually takes a few minutes 50 but, obviously, the time is determinable by trial. A quick stoppage of the gettering action can be made by the operator by means of the control 33 after which the blast may be turned off. The top is then swung off 55 of the funnel and the bracket 20 swung from under the graduate 19 by the operator who then removes the graduate. The filaments may then be dumped from the funnel 10 by pulling out the arm 12 against the action 60 of the spring 15 so that the pin 13 clears the notch and then inverting the funnel.

What I claim as new and desire to secure by Letters Patent of the United States, is:—

1. The method of coating filaments which 65 consists in projecting a number thereof into a confined space by a blast containing the coating material.

2. The method of coating filaments which 70 consists in projecting a number thereof in an upward direction into a confined space by a blast containing the coating material.

3. An apparatus comprising a substantially vertically disposed chamber having 75 communicating with the bottom thereof means for supporting a number of filaments, means for causing a blast to be directed into the bottom of said chamber, and means for incorporating coating material in said blast.

In witness whereof, I have hereunto set 80 my hand this 4th day of June, 1926.

GEORGE E. INMAN.
